Primary Examiner — Elizabeth Albert(74) *Attorney, Agent, or Firm* — J. Curtis Edmondson; Anitha Shankar Narayan; Law Offices of J. Curtis Edmondson(57) **CLAIM**

We claim the ornamental design for a dry erase board, as shown and described.

DESCRIPTION

FIG. 1 is a perspective view of a dry erase board showing my new design;

FIG. 2 is a front side view thereof;

FIG. 3 is a back-side view thereof;

FIG. 4 is a left-side view thereof;

FIG. 5 is a right-side view thereof;

FIG. 6 is a top view thereof; and,

FIG. 7 is a bottom view thereof.

1 Claim, 5 Drawing Sheets(56)
